OIL SHALE APPARATUS

Filed June 7, 1926

2 Sheets-Sheet 2

UNITED STATES PATENT OFFICE.

HOWARD E. MARSH, OF LOMPOC, AND CHARLES J. DUNTON, OF SANTA MARIA, CALIFORNIA, ASSIGNEES OF ONE-SIXTH TO VERNER E. LEE, OF SANTA BARBARA, CALIFORNIA, AND ONE-SIXTH TO JAMES H. LEE, OF GRAND JUNCTION, COLORADO.

OIL-SHALE APPARATUS.

Application filed June 7, 1926. Serial No. 114,064.

This invention relates to oil extraction apparatus and, particularly, to that type of apparatus used in the extraction of oil from oil shale.

5 One of the principal objects of the invention is to economically extract the oil from the shale.

Another important object is to provide for continuous operation of the apparatus.

10 Another object is to operate the mechanism by power developed from the heat of the burning shale.

Further objects and advantages will appear in the subjoined detailed description.

15 The accompanying drawings illustrate the invention:

Figure 1 is a view, partly in side elevation, and partly in vertical mid section, of a shale oil machine constructed in accordance 20 with the provisions of this invention, the spent shale conveyor being partly broken away.

Figure 2 is a plan view of the apparatus. There is provided a boiler 6, in this instance of the tubular type, the tubes being indicated at 7 and providing flues for the gases of combustion that rise from the combustion chamber 8 located beneath the boiler. The lower ends of the tubes 7 open through 25 a bottom plate 9 and the upper ends of said tubes open through an upper plate 10. The plate 9 forms the roof of the combustion chamber 8. Above the plate 10 is a cylindrical chamber 11, which constitutes a portion of the boiler, the gases of combustion flowing from the tubes 7 into said chamber 11. The chamber 11 is provided with a stack opening 12 for escape of the gases of combustion.

40 Within the outer portion of the boiler 6 are shale-heating chambers 13 arranged in a circle and adapted to hold the oil shale, indicated at A, and said chambers are surrounded by the water B in the boiler. The 45 chambers 13 are supplied, respectively, with shale through feed ducts 15 which extend upwardly and inwardly to a central feed opening 16, located in axial alinement with the boiler. The feed ducts are provided with gates 17 to regulate the flow of shale through said ducts, thereby controlling the speed of flow of the shale into the chambers 13.

Opening outwardly through the outer

wall 14 of the boiler are openings 18 which communicate at their inner ends with the 55 chambers 13. The openings 18 are normally closed by outwardly opening doors 19 which are hingedly mounted at 20 on the outer wall 14. The doors 19, when closed, extend aslant inwardly and upwardly and are thus 60 held by gravity in closed position. If explosion of the gases, produced from the shale, should occur, the force of the explosion will blow open the door 19 of the chamber 13 in which the explosion occurs, thus 65 preventing injury to the apparatus.

The chambers 13 are provided at their lower ends with a circular grate formed of rotary grate bars 21, 22, each of which is rotatably mounted in inner bearings 23, on 70 the outer face of the combustion chamber, and in outer bearings 24, secured to the outer wall 14. The grate bars 21 are tapered and have their smaller ends pointing inwardly and are driven by pinions 25 and the 75 grate bars 22 are mounted in pairs between the grate bars 21, and the longitudinally extending teeth 26 of the grate bars intermesh so that the grate bars 22 are driven by the grate bars 21. The grate bars 21, 80 22, are arranged radially with respect to the vertical axis of the boiler.

To drive the pinions 25, said pinions are in mesh with a ring worm gear 27 which is rotatably mounted above the pinions on 85 the outer wall of the water chamber 14 by rollers 28 rotating in upper brackets 29 and lower brackets 30, said brackets being secured to the outer wall 14.

The ring worm gear 27 is driven by a 90 worm 281 which turns in pedestal bearings 291 mounted on a suitable foundation 301. The worm 281 is turned by mitre-gears 31 driven by a shaft 32, which turns in pedestal bearings 33 mounted on the foundation 95 301. The shaft 32 is provided with a sprocket wheel 34, driven by a sprocket chain 35 from a sprocket wheel 36 mounted on the shaft 37 of a steam turbine 38.

Beneath the combustion chamber 8 and 100 chamber 13 is a funnel shaped spent shale pit 39, provided at its lowest point with an opening 40 through which the spent shale discharges into a screw conveyor 41 that is operated by mitre gears 42 from a shaft 43. 105

The combustion chamber 8 is provided

with a door 44 having an opening 45 through which extends an oil or gas burner 46 for heating the combustion chamber.

Surrounding the chamber 11 is a vapor chamber 47 through which the fuel feed ducts 15 pass, said chamber 47 communicating through openings 48 with the chambers 13, said openings 48 surrounding the lower ends of the ducts 15. In other words, the lower ends of the ducts 15 are of less diameter than the chambers 13 so that vapors or fog, as it is generally termed in this art, generated from the shale in the well, will pass upwardly through the openings 48 and into the chamber 47. This vapor thus pre-heats the shale in the ducts 15.

The vapors or fog pass from the chamber 47 through a pipe 49 which is branched, each branch connecting with the upper end of a separator 50 and provided with a valve 51. The vapors are drawn off near the lower end of the separators 50 through a branched pipe 52 which connects with an exhauster 53 direct-connected with the shaft 37. The discharge pipe 54 of the exhauster 53 may pass through a suitable condenser, not shown, for condensing the vapors drawn off from the separators.

Connected with the boiler 13 is a branched steam line 55, two of the branches provided, respectively, with valves 56 and connected with the upper ends of the coils 57. A third branch 58 of the steam line 55 connects with the turbine 38 and is provided with a valve 59.

The lower ends of the separators 50 connect by a branched pipe 60 with a rotary pump 61, each branch of said pipe being provided with a valve 62. The shaft of the pump 61 is provided with a sprocket 63 driven by a sprocket chain 64 which in turn is driven by a sprocket 65 mounted on the shaft 32. The discharge pipe 66 of the pump 61 may be connected to a suitable storage tank, not shown.

The construction and operation of the invention will be understood from the foregoing description and, briefly stated, the operation is as follows: All of the valves being closed, fire will be started under the boiler, and oil shale broken into pieces of the proper size will be delivered by a conveyor, or any other suitable means, to the opening 16 to fill the chambers 13 and the ducts 15. Then the shale in the lower portion of the chambers will be fired by any suitable means, as for example, by burners 67, in a manner well understood in this art. Steam pressure will develop in the boiler and the valve 59 will then be opened, causing the turbine 38 to operate. The turbine operates the exhauster and one of the valves 51 will be opened, thus drawing off from the shale in the chambers 13, the vapors that are given off by the shale. When the separator becomes partly choked,

its controlling valve 51 will be closed and the controlling valve 51 of the other separator will be opened immediately to permit the vapors to be drawn through said other separator. When the shale in the chambers 13 becomes sufficiently hot to maintain the requisite steam pressure in the boiler, the burners 45 will be shut off.

Having shut off the separator first used, live steam will be admitted to the coil 57 of said separator by opening the appropriate valve 56, thus producing heat to melt down the paraffin and/or other waxes that have solidified in the separator. The valve 62 associated with the separator that is being cleaned will then be opened and the operation of the rotary pump 61 will cause the paraffin and other melted waxes to be pumped out of the separator to the storage tank, not shown.

The grate bars 21, 22, rotating continuously, cause the spent shale to discharge between said bars into the pit 39, whence they discharge into the conveyor 41 and are removed by said conveyor to any suitable point of discharge. The rapidity with which the grate bars are operated determines the rate of flow of the shale through the apparatus and this is regulated by the admission of more or less steam through the valve 59 to the turbine.

From the foregoing, it is seen that the separators are used alternately so that the production of the oil will be continuous.

We claim:

1. An oil shale apparatus comprising a boiler, means to heat the boiler, a shale chamber in said boiler, means for firing the shale chamber, a feed duct leading to the upper end of the shale chamber, a grate at the lower end of the shale chamber, a vapor chamber communicating with the shale chamber, a separator connected with the vapor chamber, an exhauster communicating with the separator, and means operated by steam from the boiler to drive the exhauster.

2. An oil shale apparatus comprising a boiler, means to heat the boiler, a shale chamber in said boiler, means for firing the shale chamber, a feed duct leading to the upper end of the shale chamber, a grate at the lower end of the shale chamber, a vapor chamber communicating with the shale chamber, a separator connected with the vapor chamber and provided with a steam coil connected with the boiler, an exhauster communicating with the separator, and means operated by steam from the boiler to drive the exhauster.

3. An oil shale apparatus comprising a tubular boiler, a combustion chamber beneath the boiler communicating with the boiler tubes at one end, a chamber provided with a stack opening and communicating

with the boiler tubes at the other end, a shale chamber in the boiler, means for firing the shale chamber, a feed duct leading to the upper end of the shale chamber, a grate 5 at the lower end of the shale chamber, a vapor chamber communicating with the shale chamber, a separator connected with the vapor chamber and provided with a steam coil connected with the boiler, and a 10 burner in the combustion chamber.

4. In an oil shale apparatus, the combination of shale chambers arranged in a circle, means to fire the shale chambers, movably mounted grate bars at the lower 15 ends of the shale chambers, pinions operably connected with some of the grate bars, a rotatably mounted ring gear surrounding the shale chambers in mesh with the pinions, and means to operate said ring gear.

5. In an oil shale apparatus, the combination of shale chambers arranged in a circle, means to fire the shale chambers, rotatably mounted grate bars at the lower ends of the shale chambers, pinions connected with some 25 of said grate bars, a rotatably mounted ring gear surrounding the shale chambers in mesh with the pinions, and means to operate said ring gear.

6. In an oil shale apparatus, the combination of shale chambers arranged in a 30

circle, means to fire the shale chambers, rotatably mounted grate bars at the lower ends of the shale chambers provided with intermeshing teeth, said grate bars being tapered and, radially positioned, pinions connected 35 with some of said grate bars, a rotatably mounted ring gear surrounding the shale chambers in mesh with the pinions, and means to operate said ring gear.

7. An oil shale apparatus comprising a 40 boiler, means to heat the boiler, shale chambers arranged in a circle in the boiler, means to fire the shale chambers, movably mounted grate bars at the lower ends of the shale chambers, pinions operably connected with 45 some of the grate bars, a rotatably mounted ring gear surrounding the boiler in mesh with the pinions, a vapor chamber communicating with the shale chambers, a separator communicating with the vapor chamber and provided with a steam coil connected with the boiler, an exhauster connected with the separator to exhaust vapors therefrom, a pump connected with the separator to draw melted waxes therefrom, and a prime mover operated by steam from the boiler and operably connected with the ring gear, exhauster and pump. 50 55
